ELECTRICALLY OPERATED STOPPING DEVICE FOR HIGH SPEED ROPE-MAKING MACHINES

Josef Kraft, Olpe in Westphalia, Germany

Application June 25, 1938, Serial No. 215,933
In Germany August 17, 1937

2 Claims. (Cl. 117—51)

This invention relates to an electrically operated stopping-device for high speed rope making machines with drum carriers mounted to swing freely in a flyer and in each of which a finger is arranged directly behind each drum, said finger, in the event of breakage of the wire or the drum running empty, contacts with a contact bolt and closes a circuit.

Automatic stopping devices of the type mentioned are known in which, when a wire breaks or a drum becomes empty, a magnet is liberated which is arranged within the circular path of the wires to be twisted. This magnet actuates a switch mechanism located outside the circular path of the wires and is intended to switch off the machine and to actuate a braking device. These devices can only be fitted on machines in which the runner discs serving as bearings for the drum carriers do not form a homogenous flyer, but are each driven separately without the runner discs being in any way connected. However, as soon as the runner discs arranged spaced in tandem are connected by spacer rods or tubes distributed near the edges of the discs to form an integral flyer, as is the case in almost all twisting machines used in the wire rope making industry, these co-rotating connecting elements prevent a cooperation of the individual parts of the apparatus.

The invention relates to a stopping device, which can also be used on rope making machines whose runner discs are connected to form a single flyer and wherein the lead for the electric current is laid along the flyer.

As compared with the known current leads from rotating parts of a machine to the stationary parts thereof by means of contact springs or by means of a slip ring arranged at the side of each drum carrier, the novelty consists in that the current feed to the contact bolt is effected over a contact shaft rotatable and insulated in one of the journals of the drum carrier, which shaft is connected with branches from the current lead extending along the flyer.

Another feature of the invention consists in that the contact shaft, which runs in ball bearings mounted in insulating bushes, is connected at one end directly to the current lead and at the other end to the output wire over the ball bearing and the electricity conducting cover of the bearing bush.

An embodiment of the invention is illustrated by way of example in the accompanying drawings, in which:

Fig. 1 shows a rope making machine in front elevation with the front distance rods removed,

Fig. 2 is a part longitudinal section of Fig. 1 on a larger scale,

Fig. 3 shows a detail in longitudinal section,

Fig. 4 is a cross-section on line IV—IV of Fig. 1,

Fig. 5 shows in top plan view the wire finger hingedly mounted on a drum carrier.

The drum carriers 3 each carrying a feed drum 1 for the material to be twisted, are oscillatably mounted in the flyer 2 driven by a source of power through the intermediary of the pulley A. The flyer 2 consists of runner discs coaxially arranged one behind the other at distances apart and rotatable about a horizontal axis, these discs being connected by spacer rods or spacer tubes to form an integral whole. Each of the runner discs of the flyer rests on a pair of rotatable supporting rollers C symmetrically arranged in the base bearings B of the machine bed. The wires 4 running off the drums 1 whose uniform feeding mechanism is coupled with the machine drive in known manner, are fed at different points distributed along the flyer through the slip ring 6 mounted on the rotary shaft 5 of the machine to the laying plate 7 and thence to the closing die 9 adjustable in axial direction by a hand wheel 8a on a spindle 8 mounted in the machine frame, the finished rope being then fed to a winding drum not shown on the drawings. Electric current is supplied to the slip ring 6 from a source of power 10 by an element 11. The other end of the electric circuit is connected to the machine frame and consequently earthed.

The current flows from the slip ring 6 through the insulating wire 12 along the flyer 2. Branch wires 12a lead to each runner and connecting disc of the flyer 2 in radial direction to one of the journals 3a of each drum carrier 3 and along this carrier to a contact bolt 13 mounted thereon. The conducting of the current from the flyer to each of the drum carriers is effected by a contact shaft 14 rotatably mounted in one of the journals 3a of the drum carrier in the axial direction of the machine. The contact shaft has at its ends terminals 14a and 14b respectively for connecting to the lead 12a. The insulation of the contact shaft 14 from the journal 3a is effected by bearing bushes 15 of non-conductive material such as artificial resin, fitted one in each end of the journal. Ball bearings 16 are mounted in the bushes 15 for reducing as far as possible the frictional resistance of the rotating contact shaft 14. The steel ball bearings 16 are closed on their outer sides by covers 16a, 17 fixed on the bearing bushes 15. The cover 16a at the input end of the electric circuit is made of insulat-

ing material, whereas the cover 17 on the conducting or output end serves as conductor. The contact is established by the cover bearing against the ball bearing. An annular space acting as an insulating layer is formed between the wall of the bore in the journal and the contact shaft 14 mounted therein. A stirrup-shaped lever 18 is hingedly mounted as finger on a transverse bar 3b of the drum carrier 3. The apex of the lever 18 bears against the wire 4 running off the drum 1. If this wire breaks, or the drum becomes empty, the lever 18 swings down by gravity on to the contact bolt 13 and thus closes the circuit. This position of the finger 18 is indicated by broken lines in Fig. 2. The closing of the circuit results in a magnet attracting an armature in known manner thereby actuating a mechanical cut out and braking device and stopping the machine.

The stopping device may advantageously be coupled with a known acoustic or optical signalling device which indicates the starting up of the mechanical devices.

The operation is as follows:

When the machine is running, the contact shaft 14 of each runner and connecting disc of the flyer 2 is rotated by the lead wires 12a. This shaft leads the electric current through the ball bearing 16 to the cover 17 and thence along the drum carrier 3 to the contact bolt 13. If a wire 4 breaks or a drum 1 becomes empty, the finger 18 loses its support and consequently swings downward on to the contact bolt 13 closing the circuit.

I claim:

1. An electrically operated stopping device for high speed rope making machines comprising in combination with the flyer with drum carriers freely oscillatable therein, contact bolts one in each of said carriers below the running off wire, a circuit connected to said bolts and earthed, journals supporting said carriers in said flyers, contact shafts one rotatably mounted and insulated in one of the journals of each carrier, wires one connecting each of said shafts to one of said contact bolts, a lead wire in said circuit extending along said flyer, and branch wires leading from said lead wire to each of said shafts to supply current to said bolts through the intermediary of said shaft and said connecting wires, and fingers one hingedly mounted on each of said carriers normally supported by the corresponding running off wire and adapted to contact with the corresponding bolt when unsupported by its wire.

2. In a stopping device as specified in claim 1, insulating bushes one in each end of the carrier journals carrying a contact shaft, ball bearings one in each of said bushes, a cover of insulating material on the outer side of one of said ball bearings, and a cover of insulating material on the other side of the other of said ball bearings, the contact shaft being directly connected at one end to a branch wire and at the other end to the connecting wire through the wall bearing and the cover of conductive material.

JOSEF KRAFT.
